UNITED STATES PATENT OFFICE.

MORRIS L. ORUM, OF PHILADELPHIA, PENNSYLVANIA, ASSIGNOR OF ONE-HALF INTEREST TO CHARLES H. MELLOR.

IMPROVEMENT IN GAS-BRACKET MATCH-SAFES.

Specification forming part of Letters Patent No. 144,283, dated November 4, 1873; reissue No. 6,079, dated October 6, 1874; application filed August 14, 1874.

To all whom it may concern:

Be it known that I, MORRIS L. ORUM, of the city and county of Philadelphia, in the State of Pennsylvania, have invented a new and useful Improvement in Gas-Bracket Match-Safes, of which the following is a specification:

My invention relates to an improvement in constructing and arranging match-safes, and consists in a combined gas-bracket back and match-safe, as hereinafter described.

In the accompanying drawing, Figure 1 is a front elevation of a gas-bracket match-safe embodying my improvement; and Fig. 2, a horizontal section of the same at the line $x-x$ of Fig. 1.

The gas service-pipe C projects from the wall A, passing through an opening in the bracket-back D. The bracket-pipe B, which carries the gas-burner, is screwed upon the end of the service-pipe C, and retains the bracket-back D in position. The bracket-back is extended laterally in one or both di-

rections, and has a match-safe or safes, E, attached to it.

The bracket-back may be attached to the wall by means of screws or nails or in any other suitable manner, should the friction caused by the bracket-pipe in connecting it with the service-pipe be insufficient to keep the bracket-back in position. The safes may be in any convenient form, and of any style of workmanship, so that the bracket will present a neat and artistic appearance.

I prefer a safe or box on each side of the bracket-back of uniform size and design, as one may be used for matches and the other for the stubs, but I do not confine myself to any particular number.

I claim as my invention—

A combined match-safe and gas-bracket back, as a new article of manufacture.

MORRIS L. ORUM.
